UNITED STATES PATENT OFFICE

2,454,693

AIRPLANE CONTROL TOY

Charles H. Foster, New York, N. Y.

Application August 9, 1948, Serial No. 43,264

1 Claim. (Cl. 46—1)

1

Among the objects of my invention is to provide a toy which a child may operate to simulate the movements of an operator of an airplane, and which has pictorial means for disclosing to the child the results of his operations. With my device the child may satisfy his desire for play and indulge his desire for control of an airplane. My device is safe and affords some degree of practice and instruction in handling controls as well as delighting and amusing the child.

My invention also contemplates such other objects, advantages and capabilities which are inherently possessed by my invention and which will later more fully appear.

While I have shown in the accompanying drawing a preferred form of my invention, yet I wish it understood that the same is susceptible of modification and change without departing from the spirit of my invention.

Referring to the drawings, Fig. 1 is a face view of my toy; Fig. 2 is a front view of the dials and back member; Fig. 3 is a detailed sectional edge view on line 3—3 of Fig. 1; Fig. 4 is an enlarged detailed sectional view on line 4—4 of Fig. 1; and Fig. 5 is a diagrammatic view of the back of the discs showing mechanism.

The embodiment selected to illustrate my invention comprises a panel or board 10, having a pair of substantially centrally located spaced openings 11 and 12. At the top of the margin of the left opening 11 is the indicia "Turn and bank indicator," below which on either side are indicated 30°, 20° and 10°. At opposite lower marginal portions appear "Left bank," with "Danger" below and "Right bank" with "Danger" below. At the top of the margin of the right opening 12 is the indicia "Inclinometer." At the middle between openings 11 and 12 is the horizontal arrow with the word "Level flight." On the margins of opening 12 above "Level flight" are the markings 10°, 20°, 30° "Climb" and beyond "Stall point—Danger." On the margins of opening 12 below "Level flight" are the markings 10°, 20° and 30° "Dive," and beyond, "Danger."

At the upper left hand corner of panel 10 is an air speed indicator 13 in circular form dialing miles per hour from 0 to 1000. A finger 14 is rotatably mounted to panel 10 at the center of air speed indicator 13 and is manually operable.

At the lower left hand corner of board 10 is the marking "Radio telephone." A cord 15 extends through panel 10 and is knotted therebehind. The cord 15 extends to a toy telephone head set 16. A hook 17 is attached to panel 10 to receive head set 16 when not in play use.

2

At the upper right hand corner of panel 10 is a simulation of a toy gyro compass 18 with directions N, S, E and W indicated. A finger 19 is rotatably mounted to panel 10 at the center of compass 18 and is manually operable.

At the lower right hand corner of panel 10 is the marking "Intercom mike" adjacent a cord 20 which extends through panel 10 and is knotted therebehind. The cord 20 extends to a toy microphone 21. A clamp 22 is attached to panel 10 to receive microphone 21 when not in use.

A plate 23 has its vertical portion 24 attached to the lower central portion of panel 10. A sleeve 25 has a right angled plate portion 26 which is attached to vertical portion 24 of plate 23. A handle member or control wheel 27 has a boss 28 against which abuts the forward end of sleeve 25, and within which is rigidly attached the forward end of column 29. Column 29 extends rearwardly within sleeve 25 and is smaller in diameter than sleeve 25 so that it may move freely with relation thereto. Attached to the rear portion of column 29 and extending rearwardly therefrom is an extension 30, angular in cross section, which will act as a key, as hereinafter described.

A back member 31 is spaced from the rear surface of panel 10 but attached thereto by screws 32 removably engaging screw threaded sleeves 33 mounted in panel 10.

30 A pair of spaced turntables or discs 34 and 35 are rotatably mounted on pins 36 attached to back member 31. Left turntable 34 has marked thereon a front view of an airplane. Right turntable 35 has marked thereon a side view of an airplane.

35 Attached to the rear face of left turntable 34 is a central undercarriage 36 in which is cut a plurality of gear teeth 37. A pivot member 38 is pivotally attached to back member 31, below and to the right of left turntable member 34, and has at its upper extent a plurality of gear teeth 39 engaging gear teeth 37. Pivot member 38 has a keyway 40 to receive the end of angular extension 30.

40 To the rear face of right turntable 35 is attached a central undercarriage 41 and spaced therefrom marginal block 42. A cord 43 is attached at its inner end to block 42 and extends through eyelet 44 attached to back member 31 to column 29 where it is attached at its inner end. A spring 45 is attached to undercarriage 41 to exert a counterclockwise pressure on turntable 35.

45 A piece of isinglass or other transparent material 46 is attached to the rear surface of panel

10 and forms a pair of windows for openings 11 and 12.

An adjustable attaching means 47 is attached to the panel 10 and is adapted for attaching the device to a desired object such as a table for operation.

In use, when the child rotates the handle or steering wheel 27 to the left, column 29 rotates with it to the left. This moves extension 30 in keyway 40 and moves gear teeth 39 of pivot member 38 which move gear teeth 37 in left turntable 34, so that the left wing of the airplane representation thereon dips. By movement of the handle by the child to the right, the right wing of the airplane representation correspondingly dips.

By the child moving the handle 27 inwardly toward him, column 29 pulls cords 43 outwardly and moves right turntable 35 clockwise so as to move the airplane representation to an inclined, upwardly flying position. By moving the handle outwardly away from him, the child correspondingly moves the airplane representation on turntable 35 to a downwardly flying position.

Having thus described by invention, I claim:

An airplane control toy comprising a panel having a pair of spaced openings therethrough, a back member spacedly attached to and positioned behind and substantially parallel to said panel, a pair of spaced turntables rotatably attached to said back member and respectively positioned behind said spaced openings of the panel, said turntables each bearing a representation of an airplane, a plate attached to said panel, a sleeve attached to the face of said plate, a column having its rear portion movably positioned within said sleeve, a handle attached to the front end of said column, an angular ex-

5 tension attached to the rear portion of said column and extending rearwardly therebeyond, a pivot member pivotally attached to said back member and having a plurality of gear teeth, an undercarriage attached to the surface of one of said turntables, said undercarriage having a plurality of gear teeth engaging the gear teeth of said pivot member, said pivot member having a key-way, said angular extension extending into 10 said key-way, said handle adapted to turn and upon being turned adapted to move said column, said angular extension, said pivot member and the turntable geared thereto to move said airplane representation thereon, a cord attached at one end to said column and at the other end to the 15 other of said turntables, said handle upon being moved forwardly moving the column likewise and pulling the cord whereby to turn the other turntable and move the airplane representation thereon, a spring member attached to said other turntable to move the turntable in the reverse direction when the handle is moved rearwardly.
